UNITED STATES PATENT OFFICE.

ERNEST E. DORSEY AND HENRY J. REGE, OF CHICOPEE FALLS, MASSACHUSETTS.

COMBINED SALT AND PEPPER SHAKER.

Application filed September 6, 1924. Serial No. 736,299.

To all whom it may concern:

Be it known that we, ERNEST E. DORSEY and HENRY J. REGE, citizens of the United States, residing at Chicopee Falls, in the county of Hampden and State of Massachusetts, have invented new and useful Improvements in a Combined Salt and Pepper Shaker, of which the following is a specification.

10 This invention relates to improvements in combined salt and pepper shakers or holders in which the body part of the shaker is suitably divided to form separate compartments for receiving the salt and pepper. 15 Broadly, it comprises a suitably shaped body portion which is formed with a partition plate that extends from the bottom to the upper inside bottom portion of the cap or cover, said cap being made removable and arranged with its upper surface in a plane that is inclined to the horizontal. The cap is provided with movable slides which are located over the compartments and means for normally retaining each of 20 the slides in a normally closed position. Means is also provided for permitting the cap or cover to be readily removed from the container yet retained in place when in use.

30 Referring to the drawings:

Fig. 1 is an external side elevational view showing the cap in place.

Fig. 2 is a vertical sectional view on a plane represented by the line 2—2 of Fig. 35 1 and illustrating the partition within the body portion of the container also illustrating the two movable closure plates on the top of the cap.

Fig. 3 is a vertical sectional view on the 40 line 3—3 of Fig. 2 looking in the direction of the arrows.

Fig. 4 is a perspective view showing a portion of the upper end of the holder with the cap removed and illustrating the two 45 compartments and its inclined upper edges.

Fig. 5 is a top plan view of the cover showing the two movable perforated members.

Fig. 6 is a rear elevational view of Fig. 5 looking from the right showing the rear portion of the cap with the depending parts for operating the movable perforated slides.

Fig. 7 is a horizontal sectional view on the line 7—7 of Fig. 3, and

55 Fig. 8 is an enlarged detail view of the upper end of the holder showing the man-

ner of securing the movable perforated slides to the cap.

Referring to the drawings in detail:

1 designates the body portion of the container within which is located the partition plate 2 to provide the two separate compartments 3 and 4. 5 designates the bottom portion of the container to which the plate 2 is secured by soldering or in any other suitable way. The upper end of the body part 1 is formed with the front and rear substantially parallel portions 6 and 7. The portion 7 being of greater height than the portion 6. 8 designates as a whole, the removable closure or cap for the body part 1. The front and rear sides of this cap are indicated at 9 and 10. The front side 9 being of a length equal to the portion 6 and the rear side 10 of a length equal to the portion 7. The cap is retained in place by slightly indenting the parts 6 and 7 as indicated at 6' and 7'. These side portions are connected together by the integral part 11. It is to be understood that the integral part 11 of the cover is also integrally connected to the other two depending sides 11² and 11³, see Fig. 2, and forms a four sided cover member. It will be noticed from Fig. 4 that the interiorly located partition 2 extends upward so that its extreme upper end, indicated at 12 is in the same plane as the upper ends of the body portion 1 which are designated by the numerals 13, 14, 15, and 16. The upper end 12 of the partition therefore engages the lower under side of the integral part 11 of the cap thus preventing the possibility of the contents in the compartments 3 and 4 from passing from one side to the other.

Located on the integral portion 11 are the two perforated slidable plates 17 and 18. The part 17 is formed with the perforations 19 and the part 18 is formed with the perforations 20. These perforations are smaller than the perforations 19 for permitting the pepper in the compartment 3 to escape. The said slidable plates 17 and 18 are retained in place on the integral part 11 by means of the screws 21 and 22. The shank portion of these screws are located in the elongated slots 23 and 24 of the part 11 of the cap, whereby they may be permitted to move a definite distance on the member 11. The part 11 is formed with two sets of perforations 25 which will register with the openings 19 and 20 in the

slidable parts 17 and 18 when the slidable plates 17 and 18 are moved downward into the dotted line position shown in Fig. 8. For separately operating the perforated plates 17 and 18 the downwardly extending thumb portions 26 and 27 are provided on each plate respectively. These are an integral part of the movable plates 17 and 18 and afford a convenient piece for operating the slidable plates as shown in Fig. 8. The inner edges of the parts 26 and 27 are bent inward as indicated at 28 for the purpose of retaining the expansion springs 29 in place. These springs are for the purpose of normally retaining the movable plates 17 and 18 so that the perforations 19 and 20 are normally closed. The device is used by pressing either one of the slidable members 26 or 27 depending upon whether salt or pepper is to be delivered. If desired, both slidable plates may be moved at the same time, thus permitting salt and pepper to be simultaneously delivered. It should be noticed that the inclined upper end portion of the body part 1 is for the purpose of permitting the contents to be more readily discharged without the necessity of completely reversing the position of the container in order to discharge its contents, that is to say, the inclined portion lessens the necessity of tipping the body portion through an arc of substantially 180°.

What we claim:

1. A container comprising a body member closed at its bottom and side portions, a vertically arranged partition therein for dividing the body into a plurality of compartments, a removable cap for closing the upper end of the body member and engaging the upper end of the partition, a plurality of slidable members corresponding to the number of the compartments and located on the upper surface of the cap, said slides being formed with perforations and said closure means having perforations designed to register with the said first mentioned perforations when the movable slide members are operated, and two spring means located side by side at the upper rear side of the container for retaining the slidable members in their normally closed positions, so that the perforations in the slides and cap do not register, the upper end of the container being inclined and the upper end of the cap being correspondingly inclined, said slides being movable in a forward direction when operated.

2. A container formed with a plurality of compartments, means for normally closing each of the compartments, said means comprising a removable perforated cap and two spring actuated perforated slides mounted on the upper surface of the cap and located side by side, the perforations of the cap being designed to register with

the perforations in the slides when the slides are operated and means for connecting the slides to the cap.

3. A container for the purpose described comprising a casing which is formed with closed bottom and sides, a partition plate in the container, the upper end of the container being inclined from the back towards the front side and open, a perforated closure or cap member for the open upper end of the container and formed with a single inclined upper surface which engages the inclined end of the container, the cap member having perforated, slidable members which are secured to the cap member which rests on the inclined upper end of the container, the said slidable members each having a spring located on the rear side of the container for normally retaining the perforations in the cap closed but permitting the perforations in the cap and slides to register when the springs are compressed.

4. A container for the purpose described, comprising a casing having its upper end arranged in a single inclined plane, a partition within the casing and having its upper end in the same inclined plane, a removable rectangular shaped cap having depending sides which engage the sides of the upper end of the casing, a perforated plate which is integral with the sides and constituting the upper surface of the cap, two perforated slidable plate members secured to the said perforated plate, each slidable plate member having a depending thumb piece with a turned in part, a coiled spring on each of the turned in parts of the said plate members for retaining the same in a position to close the perforations in the cap but permitting the two sets of perforations to register when the depending thumb pieces are moved against the springs, the single inclined upper end of the container and cap serving to lessen the angle that the container is to be tipped or tilted when used to discharge its contents.

5. A container for the purpose described, comprising a casing having its upper end arranged in an inclined plane, a partition within the casing and having its upper end in the same inclined plane, a cap having depending sides which engage the sides of the upper end of the casing, a perforated plate which is integral with the sides, perforated slidable members secured to the perforated plate, each slidable member having a depending thumb piece with a turned in part, a spring on each of said members for retaining the same in a position to close the perforations but permitting the two sets of perforations to register when the depending thumb pieces are moved against the springs.

ERNEST E. DORSEY.
HENRY J. REGE.
